CLAIM

The ornamental design for a wearable headgear device, as shown and described.

DESCRIPTION

FIG. 1 is a top perspective view of a wearable headgear device according to the present invention;

FIG. 2 is a rear view of the wearable headgear device of FIG. 1;

FIG. 3 is a front view of a wearable headgear device of FIG. 1;

FIG. 4 is a top view of a wearable headgear device of FIG. 1;

FIG. 5 is a bottom view of a wearable headgear device of FIG. 1;

FIG. 6 is a left side view of a wearable headgear device of FIG. 1; and,

FIG. 7 is a right side view of a wearable headgear device of FIG. 1.

The broken lines in the drawings depict portions of the wearable headgear device that form no part of the claimed design.
